Primary Examiner — Deanna L Pratt(74) *Attorney, Agent, or Firm* — Christopher S. Clancy; James H. Williams; Aimee E. McVady(57) **CLAIM**

The ornamental design for a cable tie tool, as shown and described.

DESCRIPTION

FIG. 1 is a front left side perspective view of a cable tie tool; FIG. 2 is a rear left side perspective view thereof; FIG. 3 is a left side elevation view thereof; FIG. 4 is a front right side perspective view thereof; FIG. 5 is a rear right side perspective view thereof; FIG. 6 is a right side elevation view thereof; FIG. 7 is a top plan view thereof; FIG. 8 is a bottom plan view thereof; FIG. 9 is a front elevation view thereof; and, FIG. 10 is a rear elevation view thereof. The broken lines illustrate portions of the cable tie tool that form no part of the claimed design.
